DESIGN FOR CARPET.

Specification forming part of Design No. 11,372, dated August 26, 1879; application filed August 2, 1879.
[Term of patent 3½ years.]

UNITED STATES PATENT OFFICE.

HENRY HORAN, OF EAST ORANGE, NEW JERSEY, ASSIGNOR TO HARTFORD CARPET COMPANY, OF HARTFORD, CONNECTICUT.

DESIGN FOR CARPET.

Specification forming part of Design No. **11,372**, dated August 26, 1879; application filed August 2, 1879.
[Term of patent 3½ years.]

To all whom it may concern:

Be it known that I, HENRY HORAN, of East Orange, in the county of Essex and State of New Jersey, have invented a new and original Design for a Carpet, of which the following is a specification.

The accompanying photograph illustrates my new design.

This invention relates to a new design for carpets, oil-cloths, and analogous fabrics; and consists in the novel grouping and configuration of figures hereinafter more fully pointed out.

A, B, C, D, E, F, and G are the principal figures into which the background of this carpet is divided. The figure C is surrounded by the irregular figures A, B, D, E, and F, all of which are rectangular and placed obliquely to the figure C, as shown. The figure C is a rectangle, with a semicircular projection, *a*, and a beveled corner, *b*. The figure G is a rectangle, whose sides are parallel with those

of the figure C. A rich bouquet of flowers is within the figure C. Another is within the figure A, and a third within the figure E. Leafed branches extend into and across the remaining figures.

I claim—

1. The design for a carpet, consisting of the figures A, B, C, D, E, and F, substantially as shown.

2. The design for a carpet, consisting of the figures A, B, C, D, E, F, and G, substantially as shown.

3. The design for a carpet, consisting of the figure C, having semicircular projection *a* and beveled corner *b*, substantially as shown.

The above specification of my invention signed by me this 30th day of July, 1879.

HENRY HORAN.
